UNITED STATES PATENT OFFICE

2,490,711

INTERCONNECTED PRESSURE AND FLUID
CONTROL FOR PRESSING MACHINES

Joseph M. Rupp, Fond du Lac, Wis.

Application October 10, 1945, Serial No. 621,512

5 Claims. (Cl. 38—15)

1

The invention relates generally to machines for pressing clothing or the like and more particularly to a machine of the so-called puff iron type.

The general object of the invention is to provide a novel machine of the foregoing type, the operation of which is simplified by virtue of the fact that both of the operator's hands are free at all times to handle the article being pressed, the machine being controlled entirely by the foot for all of its functions.

Another object is to provide a novel machine of the foregoing type, which is provided with a heated buck and movable buck, as well as with means for subjecting the articles to steam during the pressing, and with means for subjecting the articles to a vacuum both before and at the conclusion of the pressing operation, with both of said means operable automatically in the sequence stated as an incident to the movement of the movable buck.

A further object is to provide a novel machine of the foregoing type, which is provided with means for steaming the articles before being pressed, in addition to the automatic steaming provided for during the pressing, said means being controlled by the operator's foot.

Still another object is to provide a novel machine of the foregoing type, utilizing a single source of steam to provide the heat for the heated buck, to supply the steam for steaming the articles, and to produce the vacuum, thus simplifying its installation in the average clothes pressing shop.

Other objects and advantages will become apparent from the following description taken in connection with the accompanying drawings, in which:

Fig. 1 is a vertical sectional view, taken from front to rear, of a pressing machine of the puff iron type embodying the features of the invention.

Fig. 2 is a fragmentary sectional view taken on the line 2—2 of Fig. 1.

Fig. 3 is a rear view of the machine.

Fig. 4 is an enlarged fragmentary sectional view taken on the line 4—4 of Fig. 1.

Fig. 5 is an enlarged horizontal sectional view taken on the line 5—5 of Fig. 1.

Fig. 6 is a perspective view of the piping in the machine.

As heretofore mentioned, the present pressing machine is of the so-called puff iron type. A machine of this type is utilized in pressing and cleaning establishments for pressing portions of articles of clothing which are of such shape and size that they are difficult to handle on

2

a large pressing machine. Thus, in the case of a woman's dress, the blouse and sleeve portions thereof have small areas that require pressing but cannot be easily handled on a big machine 5 since the pressing of these parts on a big machine would involve mussing of the other parts of the dress. Because of the character of the work performed on a machine of the present type, a heavy pressure is not required. However, the 10 maximum convenience in handling the articles should be provided so that the article may be held in proper place in the machine to press a certain portion without mussing other parts of the article that have already been pressed.

15 The present machine permits the greatest convenience in its use since the operator's hands are free at all times to handle the article being pressed, the control of the machine being accomplished entirely by the operator's foot. The 20 machine not only provides for pressing but also for steaming articles during the pressing operation or at any other time desired and for applying vacuum thereto to draw air through the cloth of the articles to remove dust or to remove moisture resulting from the steaming operation.

In its preferred form, the machine comprises generally a frame structure supporting a lower immovable buck and an upper, swingable buck 30 cooperating therewith. Movement of the upper buck toward the lower is effected by a foot pedal. The lower buck is provided with a steam chamber so that it is heated during operation of the machine. The lower buck is also provided with means for steaming the articles being pressed and for applying vacuum thereto, as stated above. The control of the vacuum and of the steaming is automatic as an incident to the movement of the upper buck toward the lower. The machine is also so arranged that steam may be applied 35 to the article at any time regardless of the position of the upper buck, a separate pedal control being provided for this purpose. The vacuum producing means is preferably of the steam-operated type so that the entire machine may be operated from a single source of steam to heat the buck, to steam the articles, and to apply vacuum thereto.

As shown in the drawings, the machine includes 40 a frame, in the present instance comprising a base flange 10, on which is mounted an upright section in the form of a sheet 11 of metal bent to provide a curved front wall 12 and spaced side walls. The sheet 11 is cut away in front adjacent its upper end to receive a table 13 with the frame 45 extending upwardly to a height above the table 50 55

in the rear thereof, as indicated at 14. To render the frame sufficiently rigid, a cross brace 15, in the form of a plate, extends between the side wall portions adjacent their lower end, while a forwardly facing sheet 16 is secured between the side walls of the upper portion 14 of the frame.

Mounted above the table 13 at the front of the machine is a lower, fixed or immovable buck 20 and an upper, swingable buck, indicated generally at 21. Both bucks are provided with the usual padding on their coacting surfaces between which the articles are adapted to be pressed. The upper buck 21 is carried on an arm 22, which preferably is in the form of a channel to render it rigid, and the arm 22 is pivotally supported on a horizontal axis by a rod 23 extending cross-wise between the sides of the upwardly extending portion 14 of the frame.

To provide for movement of the upper buck 21 toward and from the lower buck, a spring 24 is positioned in the rear part of the machine, with the upper end of the spring hooked to the rear end of the arm 22 and the lower end of the spring secured to the frame, as at 25. The spring 24 thus tends to lift the upper buck 21 upwardly away from the lower buck 20.

To effect downward movement of the upper buck into engagement with the lower buck, a tie-rod 26 is secured at its upper end to the rear end of the channel or arm 22, and its lower end is secured to the rear end of a forwardly extending lever 27 provided with a pedal portion 30 at the front of the machine. The lever 27 is pivotally supported by a cross rod 31 carried by the side walls of the frame, and a slot 32 is provided in the cross plate 15 through which the lever 27 extends, the cross plate 15 thus serving to guide the movement of the lever.

The lower or immovable buck 20 is provided with a heating chamber 33 in its lower portion, and heat is supplied thereto from a source of steam communicating with a pipe 34. Connected to the pipe 34 is a line 35 extending to a vertically positioned pipe 36 leading to the steam chamber 33 of the lower buck 20. Thus, steam will be supplied to the chamber 33 to effect heating of the lower buck. To drain the condensate from the chamber 33, a vertically extending pipe 37 is provided, the pipe 37 being connected to a suitable drain (not shown).

Since steaming of the articles when being pressed and applying vacuum thereto are features of the machine, the lower buck is provided with a series of perforations 40 in its upper surface underlying the usual padding on the buck. The perforations 40 open from a steam chest 41 within the lower buck but separated from the chamber 33. To supply steam thereto, a line 42 branching from the pipe 34 is connected to a vertically extending pipe 43 opening into the steam chest 41. Flow of steam through the line 42 to the steam chest 41 is controlled by an automatically operated valve 44 hereinafter more fully described. Steam may also be supplied to the vertically extending pipe 43 and the steam chest 41 from a branch 45 connected to the heating line 35 and controlled by a valve 46. The valve 46 is adapted to be operated by a pedal 47 extending forwardly of the machine at one side of the pedal 30 and supported in a bracket 50 secured to the frame. The rear end of the pedal 47 is connected to the valve 46 by means of a vertically extending rod 51. Thus, by operating the pedal 47, steam may be supplied to the lower buck at any time at the will of the operator.

To apply vacuum to the lower buck, a steam-operated vacuum producing means, indicated at 52, is provided. The steam-operated vacuum producing means 52 is connected to the pipe 34 for its supply of steam by a line 53. Extending upwardly from the vacuum producing means 52 is a vacuum pipe 54 opening at its top end into the steam chest 41. Flow of steam through the pipe 53 and, therefore, application of vacuum to the lower buck is controlled by an automatically operated valve 55 mounted in the line 53. By applying vacuum to the steam chest 41, any condensate remaining therein after application of steam will be drawn downwardly through the pipe 54, and thereafter air will be drawn in through the top of the buck and any article placed thereon to effect drying thereof. The vacuum producing means 52 discharges to a drain. The four pipes 36, 37, 43 and 54 provide a support for the lower buck 20 and are preferably surrounded by a screen guard 56 to prevent the operator from contacting the hot steam pipes and to prevent the articles being pressed from contacting them.

The preliminary vacuum step serves to hold an article in place after the operator removes his hands from the article while the head is moving into pressing engagement. Thus, assuming the article being pressed is provided with pleats. The operator can arrange these pleats and hold them down with his hands, but obviously his hands have to be removed before the head contacts the work. In that short space of time, the pleats can easily shift out of position and will not be properly pressed. Another instance is in the case of a garment which overhangs the bed so that only a portion thereof will be pressed between the head and the bed. The weight of the overhanging portion will tend at least to distort the part lying on the bed, if not to cause the whole article to fall off the bed. The operator cannot hold such a garment in place until clamped by the head. The operator's hands must necessarily be removed before the head contacts the garment. The preliminary vacuum step, however, provides a means for holding such articles in place after the operator has removed his hand.

As heretofore mentioned, the application of steam and vacuum to the lower buck is automatically controlled as an incident to movement of the upper buck 21. To this end, the valves 44 and 55 are adapted to be operated through movement of the lever 27. As shown herein, each of the valves 44 and 45, which are mounted at opposite sides of the machine, is provided with an inwardly extending, spring-operated valve stem 60 slidably supported by a bracket 61 extending from the side walls of the frame. At its inner end, each valve stem 60 carries a roller 62 adapted to coact with a cam means, indicated generally at 63. The cam means in the present instance comprises a flat bar 64 secured at its lower end to the rear end of the lever 27, as indicated at 65. The upper end of the cam bar 64 is guided in a cross brace 66 extending between the side walls of the frame. The cam bar 64 is positioned so that its opposite side edges respectively engage the rollers 62 and said edges of the cam bar are provided with cam sections 67 to effect operation of the valves 44 and 55.

The cam sections 67 are so positioned that, during the initial portion of the depression of the pedal 30, steam is admitted to the vacuum-producing device 52 by the valve 55 to apply vacuum to the lower buck. As the upper buck 21 approaches its lowermost position, the vacuum

is shut off, and at substantially the same time the valve 44 is opened to permit steam to enter the steam chest 41. This permits the articles being pressed to be steamed during the time when pressure is exerted thereon. When the pedal 30 is released to permit the spring 24 to raise the upper buck 21, the valve 44 is shut off shortly after the upward movement starts. Just after the valve 44 is closed, the valve 55 is opened to create a vacuum in the pipe 54. Such vacuum first withdraws any condensate within the steam chest 41 and thereafter draws air downwardly through the article being pressed to remove the moisture imparted thereto during the steaming. An operator soon becomes accustomed to using the pedal 30 for this purpose and, therefore, can prolong the steaming and application of vacuum to the articles as long as he desires. Should it be desired to apply steam to an article when the upper buck 21 is raised, the operator depresses the pedal 47 and permits steam to flow to the steam chest from the branch line 45.

From the foregoing, it will be apparent that I have provided a novel pressing machine of the puff iron type. The operation of the machine is simplified since the operator's hands are free at all times to handle the article being pressed. The entire control of the pressure between the two bucks as well as the control of the steaming and application of vacuum is exercised by the operator's foot. The application of steam and vacuum occurs automatically in a predetermined sequence as an incident to the operation of the movable buck, and may be prolonged as desired by the operator by simply holding the pedal 30 in the desired position. For steaming when the bucks are open, the pedal 47 provides a ready means for effecting such result. The machine is readily adaptable for use in the average cleaning and pressing shop since heating of the buck, steaming and application of vacuum are all operated from a single source of steam. Shops of this character invariably have such a source for various operations and, therefore, the machine fits in with other equipment used in the shop. While I have shown herein a pair of bucks of substantial size, smaller bucks than that shown and bucks of other shapes may obviously be used upon the machine.

I claim:

1. A pressing machine of the puff iron type comprising a frame, cooperating fixed and movable bucks carried by said frame, a pedal for moving the movable buck, a source of steam, a line connecting said source with said fixed buck, steam-operated vacuum producing means connected to said source and to said fixed buck, a pair of valves respectively controlling the flow of steam to said line and to said vacuum producing means, and a single cam member connected to said pedal and having a pair of cam surfaces for operating the respective valves to supply steam and apply vacuum to the fixed buck in a predetermined sequence.

2. A pressing machine of the puff iron type comprising a frame, cooperating fixed and movable bucks carried by said frame, a pedal for moving the movable buck, a source of steam, a line connecting said source with said fixed buck, steam-operated vacuum producing means connected to said source and to said fixed buck, a pair

of valves respectively controlling the flow of steam to said line and to said vacuum producing means, and a cam bar movable by said pedal adapted to operate said valves in a predetermined sequence.

3. A pressing machine of the puff iron type comprising a frame, cooperating fixed and movable bucks carried by said frame, a pedal for moving the movable buck, a source of steam, a line connecting said source with said fixed buck, steam-operated vacuum producing means connected to said source and to said fixed buck, a pair of valves located at opposite sides of said frame and respectively controlling the flow of steam to said line and to said vacuum producing means, and a bar located within said frame and movable by said pedal and having cam means on its opposite edges and adapted to operate said valves in a predetermined sequence.

4. A pressing machine of the puff iron type comprising a frame, cooperating fixed and movable bucks carried by said frame, a pedal for moving the movable buck, a source of steam, a line connecting said source with said fixed buck, steam-operated vacuum producing means connected to said fixed buck, a second line connecting said source with said vacuum producing means, a pair of valves respectively located in said lines, and a pair of cam surfaces actuated by said pedal and adapted to operate said valves, said cam surfaces being arranged to apply vacuum at the start of the movement of the one buck toward the other and to supply steam thereto during the final portion of said movement and when the bucks are engaged, and to shut off the steam and thereafter to apply vacuum during the movement of the one buck away from the other.

5. A pressing machine of the puff iron type comprising a frame, a lower buck fixedly mounted on said frame, a cooperating upper buck swingably mounted on said frame, a pedal for swinging said upper buck, said lower buck having a chest and a perforated top therefor, a source of steam, a line connecting said source with said chest, steam-operated vacuum producing means connected to said chest, a second line connecting said vacuum producing means to said source, and cam means actuated by said pedal for controlling the admission of steam to said lines and adapted to operate said vacuum producing means both before the introduction of steam into the chest to hold the work in place on the lower buck and after the introduction of steam into said chest whereby any condensate in said chest will thereby be removed.

JOSEPH M. RUPP.
